UNITED STATES PATENT OFFICE.

GEORGE L. FULK, OF CLEVELAND, OHIO, ASSIGNOR TO THE POSTAL SUPPLY & MANUFACTURING COMPANY, OF CLEVELAND, OHIO, A CORPORATION OF OHIO.

BUNDLE FORMING AND WRAPPING MECHANISM.

Application filed May 2, 1923. Serial No. 636,255.

This invention relates to a bundle forming and wrapping attachment for printing or other machines of the type in which sheets, cards, slips or the like are continuously delivered at a rapid rate.

The present invention is applicable to machines of various kinds but has been designed particularly for use in connection with the printing machine disclosed in my prior Patent No. 1,282,211, granted Oct. 22, 1918, which in operation continuously discharges at a very rapid rate printed slips which are formed by printing suitable data at intervals upon a continuous strip of material and cutting the strip, as it is discharged, into slips of a predetermined length. The printing instrumentalities of the machine are so designed that certain of the data on successive slips of a series comprising a predetermined number of slips varies and other data is constant for each series of successive slips but varies in each successive series. After their discharge from the machine the slips are wrapped in bundles, each bundle comprising one series of successively discharged slips.

The present invention is designed to automatically stack the discharged slips in a receiving magazine to periodically remove the accumulated slips from the magazine when a complete series has been deposited therein, without interfering with the continuous feeding of slips to the magazine, to convey the pack of slips so removed from the magazine to a suitable wrapping mechanism and to wrap each pack so removed while another series of slips is accumulating in the magazine. While the present invention is shown in connection with a printing machine, it is also applicable to other machines in which slips, cards or similar articles are delivered in rapid succession, the term "slips" as herein used being intended to include all articles of this character.

It is an object of the present invention to provide, in connection with a magazine to which slips of sheet material are delivered in rapid succession, a device for automatically and periodically removing a pack of slips from the magazine and wrapping the same.

A further object is to provide means for removing all of the slips from the magazine whenever a predetermined number have been delivered thereto.

A further object is to so time the opera-

tion of the slip removing means that the magazine is emptied at the instant when the last slip of the series to be removed is delivered thereto so that the magazine is emptied and ready to receive the next slip delivered from the machine.

A further object is to provide pack removing and bundling means in connection with a slip stacking magazine capable of adjustment to vary the number of slips in the bundles so formed.

A further object is to provide in connection a printing machine, a pack forming and wrapping attachment automatically controlled from a part of the printing mechanism.

A further object is to provide, in connection with a printing machine designed to print successive series of slips with varying data thereon and which may be adjusted to vary the number of slips in such series, a pack forming and wrapping attachment which is so controlled from the printing mechanism that each pack contains one complete series of such slips.

A further object is to provide means for compressing the slips in the magazine and maintaining the strips in a compact pack while they are being removed from the magazine to the wrapping mechanism and while the pack is being wrapped.

With the above and other objects in view, the invention may be said to comprise the elements and combinations hereinafter described and claimed, together with such variations and modifications thereof as will be obvious to those skilled in the art.

Reference should be had to the accompanying drawings in which Fig. 1 is a top plan view showing a part of the stacking and bundling mechanism and a portion of the printing machine to which the same is applied; Fig. 2 is a side elevation of the mechanism shown in Fig. 1; Fig. 3 is a side elevation of the slip stacking and bundling mechanism looking toward the discharge end of the printing machine, said mechanism being disposed transversely with respect to the direction of movement of the printing machine; Fig. 4 is a fragmentary perspective view showing the slip cutter and a portion of the pack forming and extracting mechanism; Fig. 5 is a fragmentary top plan view showing the slip cutter and packer; Fig. 6 is a plan view of the double cam con-

trolling the operation of the pack shifting carriage and the wire feeding and cutting mechanism; Fig. 7 is a plan view of the double cam controlling the operation of the 5 pack wrapping and wire tying mechanism; Fig. 8 is a fragmentary top plan view showing the pack receiving portion of the wrapping mechanism and the pack shifting carriage in position to deliver a pack of slips 10 thereto; Fig. 9 is a side elevation of the pack shifting carriage; Fig. 10 is a front elevation of the pack shifting carriage; Fig. 11 is a side elevation of the bundle receiving and holding portion of the wrapping mechanism 15 together with the wire guides associated therewith; Fig. 12 is a vertical section on line 2—2 of Fig. 11 looking in the direction indicated by the arrows; Fig. 13 is an elevation of the pack receiving portion of the 20 wrapping mechanism looking toward the receiving side thereof, i. e. toward the left in Figs. 3, 8 and 11; Fig. 14 is a fragmentary top plan view showing the wrapping mechanism together with the wire guides associated 25 therewith; Fig. 15 is a detail view showing the pack supporting slide in side elevation; Fig. 16 is a fragmentary top plan view showing the shiftable wire feeding carriage; Fig. 17 is a sectional elevation looking 30 toward the right in Figs. 3 and 16 and showing the wire feeding and cutting mechanism; Fig. 18 is an elevation of the wire feeding carriage from the side opposite that shown in Fig. 12; Fig. 19 is a side elevation of the 35 pawl and ratchet mechanism through which the wire feeding rolls are driven; Fig. 20 is a side elevation of the wire tying device; Fig. 21 is a top plan view of the wire tying device; Fig. 22 is a section taken on line 40 22—22 of Fig. 20; Fig. 23 is a bottom plan view of the wire tying device showing the fixed wire guiding and holding members.

Referring to Figs. 1 and 2 of the drawing, the printing machine to which the present invention is applied has an endless chain of plates A and other printing instrumentalities B between the endless chain A and the discharge end of the machine. The printing plates A and the printing mechanism B 45 operate successively upon a continuous strip of sheet material C to print the desired data upon successive portions of the strip C. The printed matter on each of the plates A is different from that of any of the other plates 50 and as many plates may be connected to the endless chain as may be desired. The subject matter printed on the strip C by means of the printing instrumentalities B is constant for each series of printed data produced by the endless chain of plates and 55 may be varied for each successive series as set forth in my prior patent above referred to. The printed matter upon the strips C is on successive portions of equal length and the strip C is cut into lengths between suc- 60

cessive printed portions at the discharge end of the machine. It will thus be seen that successive series of slips are formed, the number of slips in the series depending upon the number of plates in the endless chain. 70

The present invention is designed to automatically form each series of slips into a compact pack or bundle as the slips are delivered from the machine and to individually wrap each pack or bundle so formed. 75 The arrangement of the various parts of the bundling and wrapping mechanism is best shown in Fig. 3 of the drawing in which D designates generally the strip cutting and stacking mechanism. E the transfer carriage 80 which conveys the packs of strips formed in the stacking mechanism to a wrapping device F to which the wire which is wrapped about the bundles is fed by a wire feeding and cutting mechanism G and which wraps the wire about the bundle and positions the wire to be engaged by the wire tying mechanism H.

The general sequence of operations is as follows; 90

The strip C is cut into slips of equal length as it is discharged from the printing machine, the strips are stacked and compressed in a suitable magazine and at suitable intervals are stripped from the magazine into the transfer carriage E which as soon as the transferring operation is completed is shifted toward the wrapping mechanism F. Simultaneously with the actuation of the carriage E the wire feeding mechanism G is started into operation and delivers a suitable length of wire to the wrapping mechanism. When the carriage E has positioned the pack of slips directly over the wrapping mechanism F, the wrapping mechanism F is actuated to wrap the length of wire which has been delivered to it about the bottom and sides of the pack of slips and to position the ends of the wire between the clamping jaws of the tying mechanism H, the operation of which is so timed that it begins to operate upon the completion of the movement of the wrapping mechanism. During the tying operation, the transfer carriage E is moved back to its original position beneath the slip receiving magazine ready to receive another pack of slips. The mechanism actuating the carriage wire feeding and wrapping and tying mechanism being disconnected upon the return of the carriage E to its feeding position. 100

The strip C after passing through the delivery rolls of the printing machine slides over the bed 1 of the printing machine, adjacent the end of which is a magazine 2 to receive the slips and a disc 3, at the edge of the bed 1, which is continuously rotated at a proper speed to cut slips of the desired length, the disk 3 being provided with a 105 110 115 120 125 130

blade 4 projecting from the periphery thereof. The blade 4 moves across the edge of the bed 1 and severs the strip C each time that it moves across the end of the bed 1.

5 As shown in Fig. 5 the magazine 1 is provided with a follower 5 which is carried by a slide 6 which moves in a vertical undercut slot in the post 7 at the rear of the magazine, the slide 6 being suspended by a suitable coil spring 8 so that the slips in the 10 magazine are subjected to an upward pressure and the follower 5 will instantly return to its uppermost position after the pack of slips has been removed therefrom.

15 The slips which are forced down into the magazine as they are discharged from the printing machine are retained against upward movement by means of suitable spring latches 9 which are pivoted to suitable 20 brackets outside the magazine and project through suitable slots into the magazine. A short distance above the uppermost position of the follower there is a yielding support for the slips in the form of bars 10 which 25 are pivoted to suitable brackets outside the magazine adjacent its inner and outer ends and project through slots 11 in the front and rear walls thereof. The bars 10 are normally held in horizontal position by means of 30 coil springs 12 which are connected to the outer ends of the bars and to the magazine beneath the same. The first slips delivered into the empty magazine are deposited upon the bars 10 which are gradually forced down 35 as the slips accumulate until the slips rest upon the follower 5 and the bars 10 occupy a vertical position in the slots 11. The purpose of the bars 10 is to provide means for receiving and holding a number of slips fed 40 to the magazine while a pack upon the follower 5 is being discharged and the follower 5 is returning to receiving position. The slips as they are severed by the knife 4 are forced down into the magazine and past 45 the latches 9 by means of striker arms 13 which operate in slots 14 in the front and rear walls of the magazine. The striker arms 13 are rigidly attached to a horizontal block 15 having trunnions at its ends which 50 are journaled in a channel bracket 16 at the rear of the magazine. The arms 13 are clamped to the block 15 by means of a plate 17 bolted to the upper face of the block 15 so that the arms 13 can be quickly 55 replaced if broken or bent during the operation of the machine. Rigidly attached to the inner end of the block 15 is an upwardly extending arm 18 which is connected by means of a link 19 to the outer face of the 60 cutter disk 3 so that at each revolution of the disk 3 the arms 13 are swung down into the magazine and returned to a position clear of the magazine. The connection between the oscillating arms 13 and the rotary 65 disk 3 is such that the arms 13 are above the magazine and clear of the incoming strip as it is being delivered to the magazine and when the knife 4 moves across the end of the bed 1 to sever a strip, the arms 13 are moving alongside the knife so that the strip 70 is instantly forced down into the magazine.

When a complete series of slips has been delivered to the magazine 2, the pack of slips in the magazine is automatically stripped from the magazine and delivered 75 into the transfer carriage. The pack stripping mechanism which is best shown in Figs. 3 and 4 will now be described:—

The slips are stripped from the magazine by means of a stripper arm 20 which 80 has a forwardly projecting hook portion 21 adapted to be projected into the magazine and to engage the top of a pack of strips therein. The stripper arm 20 has a laterally projecting pin 22 adjacent its upper end which travels during its upward and downward movement in parallel grooves 23 and 24 formed in the outer face of the vertical post 7. The grooves 23 and 24 are connected at their upper and lower ends and the pin 22 is caused to move from one groove to the other by means of gate cams 25 and 26, the upper of which is set to cause the pin to travel from the rear groove 24 to the forward groove 23 and the lower of which 90 is set to cause the pin 22 to travel from the forward groove to the rear groove. The hook 21 in the movement of the stripper arm is thus caused to project into the magazine above the pack of slips therein during downward movement of the stripper arm and to clear the magazine during the upward movement of the stripper arm. The stripper arm 20 is pivoted at its lower end to a slide 27 95 which travels in a vertical groove 28 formed in the outer face of the vertical post 7. A rearwardly projecting link 29 is pivoted at its forward end of the slide 27 and at its rear end to the upper end of a link 30 which in turn is pivoted at its lower end to the frame. 100 A strong coil spring 30^a is connected at its upper end to the link 29 and at its lower end to a suitable fixed support and serves when the stripper arm is relaxed to move the slide 27 downwardly at a rapid rate to strip the 105 slips from the magazine. The stripper arm 20 is normally retained in its uppermost position by means of a latch 31 which is pivoted to the post 7 and engages a suitable lug 32 at the upper end of the arm 20. The lug 32 is engaged by the latch 31 just after the pin 22 has passed the upper spring pressed gate 25 of the cam groove and holds the upper end of the arm 20 against movement toward the magazine, the pin 22 being 110 in engagement with the inclined upper face of the gate 25 which holds the stripper arm against downward movement. The latch bar 31 is normally held in engaging position 115 by means of a coil spring 33 which is at 120 125 130

- tached to the outer end of the latch bar and to the rear face of the post 7 above the same, the downward movement of the latch bar 31 being limited by a suitable stop pin 34. It will thus be seen that whenever the latch bar 31 is moved to release the lug 32, the stripper arm will be instantly actuated to discharge the slips from the magazine and that when the stripper arm is returned to its uppermost position by suitable means, the lug 32 will be engaged by the latch bar 31 and the stripper arm 20 will be retained in its uppermost position until it is again released by actuation of the latch bar. For actuating the latch bar 31 at suitable intervals, a link 35 is connected to the rear end thereof and extends downwardly and is attached at its lower end to the outer end of a link 36 which is pivoted at its inner end to the bracket 16. A trip bar 37 is pivoted intermediate its ends to an intermediate portion of the link 36 and is connected at its lower end to a coil spring 38 which in turn is connected to the bracket 16 adjacent the outer end thereof. A trip wire 39 is also connected to the lower end of the trip arm 37 and extends along the printing machine to an actuating lever 40 which is mounted on a horizontal pivot alongside the endless chain A and overlies the upper run of the chain. A striker plate 41 is attached to the underside of the block 15 and projects forwardly over the link 36. The trip arm 37 is normally held clear of the striker plate 41 by means of the coil spring 38, but whenever the lever 40 is engaged by a lug 42 which is carried upon one of the links of the endless chain A, the trip arm 37 will be swung over under the trip plate 41 so that it will be engaged by the trip plate upon its downward movement, swinging the link 36 downwardly and lifting the latch 31 out of engagement with the lug 32 of the stripper arm 20. As hereinbefore set forth the movement of the striker arm 13 is so timed that at the instant of the cutting operation as the knife 4 severs a slip, the arms 13 move downwardly into engagement with the slip. The movement of the striker plate, since it is rigidly attached to the same support as the arms 13 corresponds exactly with the movement of the arms so that when the trip member 37 has been actuated by the lug 42, the striker plate 41 engages the same at the instant when a strip has been severed by the knife 4 so that the stripper which is instantly actuated upon the release of the latch 31 has a maximum time in which to discharge the slips from the magazine so that the bars 10 may move to supporting position in time to receive the next slip delivered to the magazine. By reason of the fact that the lug 42 is carried by one of the links of the endless chain of plates A, the stripping mechanism is so timed as to discharge upon each

actuation a complete series of slips, the lug 42 being so positioned that it actuates the lever 40 at the instant when the last slip of a series is being delivered into the magazine. Since the endless chain A may be of any desired length according to the number of slips in a given series, it is obvious that the actuation of the stripper will be varied accordingly. 70

In addition to the actuation of the stripper, the trip mechanism above described also serves to start into operation the mechanism which actuates the transfer carriage E, wire feeding mechanism G and the wrapping and tying mechanisms F and H. The means for 80 effecting the operation of these parts will now be described;

A lever 43 is pivoted to the frame on a horizontal pivot intermediate its ends beneath the slide actuating link 29 and has an upwardly curved rear end 44 overlying the support to which the link 30 is pivoted. The rear end of the lever 43 is connected by means of a link 45 with a trip arm 46 which is pivoted to the upper end of a clutch shifting lever 47 and normally engages with a lug 48 upon the rear edge of the transfer carriage actuating lever 49. The clutch lever 47 has a part engageable with a clutch collar 50 upon a shaft 51 which has loosely mounted thereon a constantly driven belt pulley 52. The clutch collar 50 is connected with a suitable clutch, not shown, for connecting the belt pulley 52 to the shaft 51. Upon actuation of the stripper mechanism above described, the slide 27 in its downward movement strikes the forward end of the lever 43 swinging the same downwardly and through the link 45, shifting the trip arm 46 upwardly until it clears the lug 48. When the trip arm 46 is released from the lug 48, the clutch lever 47 is actuated by means of a suitable spring to force the clutch into engaging position and to drive the shaft 51 through the belt pulley 52. The shaft 51 serves to actuate the bundle shifting wrapping and tying mechanisms. A brake disk 53 is fixed to the shaft 51 inside the driving pulley 52 and the clutch lever 47 is provided with a brake arm 54 which carries a brake shoe 55 which is moved into engagement with the disk 53 as the clutch lever 47 is actuated to disengage the clutch. This brake mechanism serves to instantly stop the shaft 51 upon disengagement of the driving pulley. 110

The mechanism for shifting the packs of slips from the magazine and wrapping and tying the same are actuated by means of two double cams 56 and 57 carried by a transverse shaft 58 which is driven by suitable gearing, not shown, from the shaft 51. The carriage actuating lever 49 carries a roller 59 intermediate its ends which travels in a cam groove 60 on the inner face of the cam 130

disk 56 and actuates the transfer carriage E through a link 61 which is connected to the carriage and to the upper end of the lever 49.

5 The cam disk has a cam groove 62 upon its outer face which receives a roller 63 which is carried by a lever 64 which is pivoted to the frame at its rear end and is connected at its forward end to the vertically 10 movable slide of the wrapping mechanism F.

The cam disk 57 has a cam groove 65 on its inner face which receives a roller 66 at the rear end of a lever 67 which is pivoted intermediate its ends to the frame and at its 15 forward end to a vertical connecting rod 68, which is in turn connected to one arm of a bell crank lever 69, the other arm of which is connected by means of a link 70 to the slide 71 which actuates the wire tying 20 mechanism. The cam disk 57 has a cam groove 72 on its outer face which receives a roller 73 which is carried by a lever 74 at the rear of its pivot, the lever 74 being connected through a yielding link 75 to a 25 vertically sliding rack bar 76 which actuates the wire feeding and cutting mechanism G. The rear end of the lever 74 is connected to an upwardly extending link 77 to the upper end of which is connected a link 77^a pivoted intermediate its ends upon the pivot pin connecting the stripper actuating links 29 and 30 which form a toggle connection between the stripper slide 27 and the frame of the machine. At its forward end the 30 35 link 77^a has an outwardly projecting pin 77^b which is engaged by the link 29 when the slide 27 is in its lowermost position. As the cam disk 57 begins its revolution, the link 77 is pulled downwardly swinging the forward end of the link 77^a upwardly, causing the toggle formed by the links 29 and 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 has been delivered to the carriage, the hooks being mounted upon the inner sides of the standards 82. Adjacent their lower ends and below the pivots thereof the retaining hooks 88 are provided with outturned lips 91 which project behind the rear edges of the standards 82 and are engaged by spring pressed plungers 92 carried by the standards 82 which serve to normally hold the retaining hooks in pack engaging position. Adjacent their upper ends the hooks 88 are provided with outturned lips 93 which project behind the rear edges of the standards 82 and carry set screws 94 which engage with the rear of the standards to limit the forward movements of the hooks, the set screws 94 permitting adjustment to vary the extent of forward movement of the hooks. In order to provide means for properly receiving and retaining packs of different sizes, the pack supports 83 are attached to the upper ends of vertically movable rack bars 95 which are engaged by pinions 96 which are driven through intermediate pinions 96^a from pinions 96^b carried by a transverse shaft 97 journaled in the base 78 of the carriage. The shaft 97 has a hand wheel 98 at its outer end by means of which it may be rotated to adjust the retaining hooks. The shaft 97 is held in adjusted position by means of a spring pressed detent 99 which engages with any one of a circumferential row of indentations 100 in the shaft 97. The shaft 97 is retained against longitudinal movement by means of a fixed pin 101 which engages within a circumferential groove 102 in the shaft.

As clearly shown in Fig. 3 when the carriage is in its rearmost position beneath the magazine 2, the hook 88 is held clear of the pack receiving channel between the standards 82 by means of the lever 43, the forward end of which engages with the hook 88 below the pivot thereof holding the hook portions 90 in a position behind the standards 82. When the slide 27 engages the lever 43 the lever is swung down out of engagement with the lower end of the hook 88 and the hook 88 is released and swung by means of the spring pressed plunger 92 into pack engaging position. The hooks 88 are thus caused to engage the top of the pack at the instant when the pack is delivered to the carriage and before the stripper hook begins its upward movement to retain the pack under pressure in the carriage. The stripper hook 20 moves upwardly out of engagement with the pack before the carriage has moved forwardly sufficiently to release the follower 5 so that there is no danger of damaging the top slip by dragging it out from under the point 21 of the hook 20. The hooks 88 are closely adjacent the standards 82 and leave ample space between them for the follower 5 to return to

the magazine as soon as the carriage E has moved forwardly a sufficient distance to move the pack off of the follower.

Referring to Figs. 3 and 12 to 15 inclusive, the wrapping mechanism is carried upon the vertically movable slide 103, the lower end of which is suitably connected to the actuating lever 64. The slide 103 is provided with a transverse slot 104, the width of which is just sufficient to receive a pack of slips supported upon the carriage. The slide has vertical arms 105 and 106 at the front and rear of the slot, the arm 105 being detachably secured in place by means of screws 107. Centrally of the pack receiving slot 104 there is a vertical rod 108 which extends substantially the full length of the slide 103 and is slidably mounted therein. The rod 108 carries the pack supporting block or follower 109 at its upper end, the block 109 fitting slidably between the vertical arms 105 and 106. The block 109 is normally held in its uppermost position with respect to the slide by means of a long coil spring 110 surrounding the rod, bearing against the underside of the block 109, and extending to the lower end of the slide 103, the slide being bored at 111 beneath the slot 104 to receive the spring which bears at its lower end upon a bottom plate 112, which is secured to the lower end of the slide at the bottom of the bore 111. The rod 108 projects through the plate 112 and has a sliding fit therein. The rod 108 carries nuts 113 at its lower end beneath the plate 112 which serve to limit the upward movement of the rod with respect to the slide and which may be adjusted to properly position the block 109 with respect to the upper end faces of the arms 105 and 106, the top face of the block 109 when properly positioned being normally flush with the top faces of the arms 105 and 106. On one side face thereof the block 109 has vertical ribs 114 which engage in vertical grooves formed in the inner face of the detachable arm 105. The slide 103 is connected to the fixed frame-work by means of an undercut slot on the inner side of the arm 106 which engage the rib 116 of a guide rail 117 suitably fixed to the framework.

The groove of the cam which actuates the lever 64 to move the slide 106 upwardly is so designed that the slide 103 starts its upward movement just after the carriage E has reached the forward end of its movement and the groove of the cam actuating the carriage lever 49 is so designed that the carriage has a dwell upon reaching the forward end of its movement. When the slide 103 moves upwardly, the block 109 will engage the bottom of the pack which is then positioned directly over the slot 104 and aligned therewith. Since the pack is held against upward movement by the retaining hooks 88, the block 109 will recede within

the slot 104 and the arms 106 will move upwardly along the sides of the pack in the carriage, the relative movement of the block 109 being permitted by the supporting spring 108.

The function of the slide 103 in addition to removing the pack from the carriage E is to wrap a suitable length of wire about the bottom and sides of the pack and to position 10 the ends of the wire to be engaged by the tying mechanism. To enable the slide to perform the wire wrapping operation, suitable wire guiding and holding means are provided which will now be described.

15 As shown in Figs. 11, 12 and 14, a wire guiding member 118 is detachably secured within a recess at the top of the arm 106 and is secured in place by a suitable thumb screw 119. The wire guiding member 118 extends 20 horizontally and has a longitudinal bore 120 and a longitudinal slot extending the full length thereof in its upper face which communicates with the bore 120. A cylindrical wire receiving member 122 fits with 25 in the bore 120 and is provided with a longitudinal wire receiving groove 123 in which one position registers with the slot 121 of the member 118. A suitable wire guiding extension 124 (see Fig. 3) provided with a 30 wire guiding groove in its upper face is detachably secured to the end of the wire guiding member 118 and extends to adjacent the wire feeding mechanism G. Since it is desirable to feed the lengths of wire, suitable for 35 bundles of different sizes, a number of extensions 124 of different lengths will be provided, the wire feeding mechanism being adjustable toward and from the wrapping mechanism and adapted to deliver wire in different 40 lengths as will be hereinafter explained.

The pack supporting block 109 is provided with a transverse bore 125 adjacent the top thereof and with a slot 126 extending across the top and communicating with 45 the bore 125, the slot 126 being in alignment with the slot 121 of the wire guiding member 118. A cylindrical wire receiving member 127 fits within the bore 125 and has a longitudinal groove 128 which in one position of 50 the wire receiving member registers with the slot 126 in the block. A suitable wire guiding block 129 is detachably secured within a recess at the top of the arm 105 of the slide and this block is provided adjacent the 55 top thereof with a transverse bore 130 and with a slot 131 across the top thereof communicating with the bore 130. A cylindrical wire receiving and retaining member 132 fits within the bore 130 and is provided 60 with a wire receiving groove 133 which in one position of the member 132 registers with the slot 131 of the block 129. The slots 121 in the wire guiding member 118, 126 in the block 109 and 131 in the block 65 129 are in alignment so that when the

grooves 123, 128 and 133 of the cylindrical wire retaining members are aligned therewith, the wire is released so that the ends thereof can spring upwardly to vertical position to be engaged by the jaws of the tying 70 mechanism.

The cylindrical wire retaining member 122 has an arm 134 rigidly secured thereto which projects through an elongated slot 135 in the lower portion of the member 118. 75 The wire retaining member 122 is normally held in a position with its groove 123 out of alignment with the slot 121 of the member 118 by means of a lever 136, the upper end of which engages the arm 134 between the upper end portion 137 thereof, which is guided in a groove 137^a formed in the under side of the overhanging top portion of the arm 106, and a leaf spring 138 attached to the inner face of the lever 136 and yieldingly holding the arm 134 against the end portion 137 of the lever. The lever 136 is fixed adjacent its lower end to a shaft 139 which extends through the slide 103 from the rear to the front thereof below the slot 104. 80 The lower end of the lever 136 below its pivot is engaged by a coil spring 140 held under compression within a bored boss 141 on the slide. Between the pivot of the lever 136 and the upper end thereof, the lever 95 carries a set screw 142, the inner of which bears against the head of a pin 143 which is slidably mounted in a hole formed in the arm 106 and bears against the rib 116 of the guide rail. The action of the compression 100 spring 140 is to urge the lever 136 in a direction to swing the groove 123 of the wire retaining member 122 into alignment with the slot 121 of the member 118 to release the wire. When the slide is at any 105 position other than its uppermost position, this movement of the lever is prevented by the pin 142. However, when the slide approaches its uppermost position, the pin 143 rides off the inclined end portion 144 of the 110 guide rail and releases the lever 136, permitting the spring 140 to swing the lever inwardly and shift the groove 123 of the wire retaining member 122 into alignment with the slot 121 thereby releasing the wire, 115 the inward movement of the lever being limited by engagement of the arm 134 with the inner end of the slot 135.

The cylindrical wire retaining member 132 at the upper end of the arm 105 has an arm 145 which is rigidly secured thereto and projects through an elongated slot in the bottom of the block 129. This arm 145 is engaged by an arm 146 which has a rounded upper end portion 147 bearing against the arm 145 and a leaf spring 148 secured to the inner edge of the arm 146 and bearing against the arm 145 to yieldingly hold said arm 145 in engagement with the end 147 of the arm 146. The 120 125 130 135 140 145 150

lower end of the arm 143 is fixed to the shaft 139 which carries the lever 133 so that the arm 143 moves with the lever 133 to move the groove 133 of the wire retaining member 132 into alignment with the slot 131 in the top of the block 129 at the same time that the groove 123 of the wire retaining member 122 is moved into registry with the slot 121 of the member 118 so that when the slide approaches its upper limit of movement both ends of the wire are simultaneously released and permitted to spring to vertical position preparatory to the tying operation.

15 The wire retaining member 127 mounted in the block 109 is provided with a rigid arm 149 which projects upwardly through an elongated slot 150 in the block 109 and is normally held in a position in which the 20 groove 128 of the retaining member 127 is out of registry with the slot 126 in the block 109 by means of a compression spring 151 mounted in a suitable bore in the block 109 and bearing against the underside of 25 the arm 149. A suitable stop pin in the slot 150 limits the upward movement of the arm. The upper portion of the arm 149 normally projects above the top face of the block 109 and, when the slide 103 is moved vertically, 30 the arm 149 engages the bottom of the pack of slips in the carriage E and is forced downwardly into the slot 150 until its upper edge is flush with the top surface of the block. In this position the groove 128 in 35 the retaining member 127 registers with the slot 126 in the block 109 and the wire is free to move upwardly into engagement with the bottom of the pack.

As the slide 103 moves upwardly the pack 40 engaging block 109 moves upwardly with the slide until it engages the bottom of the pack, the pack being rigidly held against upward movement by the retaining hooks 88, the block 109 then recedes within the slot 104 45 and the arms 105 and 106 move up along opposite sides of the pack. During the upward movement of the slide the opposite ends of the wire are held within the retaining members carried by the upper ends of the arms 50 105 and 106 and as the block 109 recedes within the slot, the wire is drawn down into the slot and guided vertically along the sides of the pack. When the slide has just about 55 reached its upper limit of movement, the wire will have been wrapped around the bottom and sides of the pack at the center thereof and the ends of the wire will now be released and will spring to vertical position so that they can be engaged by the jaws of the 60 tying mechanism. The movement of the carriage is so timed that while the arms 105 and 106 are engaging the front and rear sides of the pack, the carriage will begin its return movement. The yielding retaining plates 84 upon rearward movement of the

carriage will swing outwardly clear of the ends of the pack freeing the carriage from the pack.

Referring to Figs. 3 and 16 to 19 inclusive of the drawing, the wire feeding and cutting mechanism G is carried by a suitable casing 153 which has a horizontally extending guide boss 154 on its inner side which is bored to receive a fixed cylindrical rod 155 upon which the casing 153 slides. The casing 153 is guided adjacent its lower end by means of depending flanges 156 and 157 which engage with the flange of a suitable guide rail 158 which is suitably secured to the frame of the machine. The casing 153 carries upon the outside thereof upper and lower wire feeding rolls 159 and 160, the bight of which is in horizontal alignment with the groove of the wire guiding members of the wrapping mechanism F when the slide 85 103 is in its lowermost position. The upper roll 159 is rotatably mounted upon a transverse shaft 161 which is carried by standards 162 upon the top of the casing 153. The shaft 161 has retaining nuts 163 and 163^a bearing against the inner face of the innermost standard 162 and against the hub of the roll 159 respectively. A collar 164 receives the shaft 161 between the standards 162 and has an integral arm 165 connected 90 at its lower end by a pivot 166 to the top portion of the casing. The collar 164 carries a set screw 167 which engages with the shaft 161 to hold the shaft against rotation. By adjusting the nuts 163 and 163^a and locking the same in adjusted position, the roll 169 may be positioned in proper alignment with the lower wire feeding roll 160. The lower roll 160 is upon the outer side of the casing 153 and is fixed to a horizontal shaft 168 which is journaled in bearing bosses 169 and 169^a formed upon the rear and front walls respectively of the casing 153. Front and rear wire guiding members 170 and 171 integral with the casing 153 are disposed opposite the bight of the rolls 159 and 160 in the front and rear thereof and are provided with conical wire receiving apertures 172 and 173 leading from and to the rolls. The wire is fed to the rolls from a suitable reel not shown and is severed after a suitable length thereof has been fed by means of a cutter which will hereinafter be described which moves across the front face of the front of the wire guiding member 170.

The lower feed roll 160 is driven from the vertical rack bar 76 through gearing mounted upon a horizontal shaft 174 which extends through the casing 153 from the front to the rear thereof and adjacent the center. Within the casing 153, a sleeve 175 is rotatably mounted upon the shaft 174 and carries a gear 176 which meshes with the teeth of the vertically movable rack bar 76 so that the sleeve 175 is rotated in one direction 110 115 120 125 130

while the rack bar 76 is moved upwardly and in the opposite direction when the rack bar 76 is moved downwardly. The sleeve 175 extends from adjacent the rear wall of the casing 153 toward the front wall thereof and between the forward end of the sleeve 175 and the front wall of the casing there is rotatably mounted upon the shaft 174 a large gear 177 which has a ratchet wheel 178 rigidly attached to its inner side. The sleeve 175 has an arm 179 attached to its forward end between the gear 176 and the ratchet 178, which arm has a pawl 180 pivoted thereto at its outer end which is adapted to engage with the teeth of the ratchet 178 and is engaged by a leaf spring 181 which tends to force the pawl into engagement with the ratchet teeth. The teeth of the ratchet 178 are so disposed that they are engaged by the pawl 180 to rotate the ratchet and with it the gear 177 during the upward movement of the rack bar 76, the pawl 180 riding over the teeth of the ratchet during the downward movement of the rack bar 76. The gear 177 meshes with a gear 182 which is fixed to the shaft 168 to which the lower wire feeding roll 160 is attached so that during the upward movement of the rack bar 76 the feed roll 160 is driven to feed a suitable length of wire to the wrapping mechanism.

In order to deliver pieces of wire of a length suitable for the size of bundle being wrapped, means are provided for varying the extent of movement of the feeding roll 160 upon the upward movement of the rack bar 76. To this end an arcuate ratchet guard 183 which overlies a portion of the periphery of the ratchet 178 is fixed to the shaft 174 between the ratchet 178 and the outer end of the sleeve 175. A crank 184 is attached to the shaft 174 outside the casing 153 and has a handle 185 which is provided with a suitable spring pressed locking pin 186 which is adapted to engage with any one of an arcuate row of apertures 187 in the casing wall. By means of the crank 184, the arcuate guard 183 can be adjusted so that any desired portion thereof is in advance of the position of the pawl 180 when the rack 76 is in its lowermost position so that the pawl 180 will ride over the surface of the guard 183 during any desired portion of the upward movement of the rack bar and the rotary movement of the feed roll 160 will be varied accordingly. It is necessary not only that different lengths of wire be fed to the wrapping mechanism, but it is also necessary that the length of wire so delivered be centered with respect to the pack engaging block 109 so that equal lengths of wire will project upwardly upon opposite sides of the pack to be engaged by the tying mechanism. To accomplish this result, means are provided for adjusting the wire feeding mechanism forwardly toward

the wrapping mechanism a distance proportional to the length of the pieces of wire being delivered to the wrapping mechanism, in the form of a gear 188, fixed to the shaft 174 at the rear end thereof outside the casing, which meshes with rack teeth 189 formed upon the under side of the guide rod 155, whereby, when the crank 184 is adjusted to vary the movement of the feed roll 160, the entire wire feeding mechanism will be moved forwardly or backwardly a proportionate distance. For severing the wire after the roll 160 has completed its feeding movement, a cutter slide 191 is mounted to move across the front face of the wire guide 170. The cutter slide 191 is slideable in upper and lower bosses 192 projecting from the front face of the casing 153, and is held against turning movement by means of a pin 193 attached thereto and working in a vertical slot 194 in the lower guide boss 192. The slide 191 is normally held in its lowermost position with its cutting edge beneath the aperture 172 of the wire guide 170 by means of a coil spring 195 mounted on the slide and bearing at its upper end against the lower side of the upper guide boss 192 and at its lower end upon a collar 196 suitably secured to the slide 191. The lower end of the slide 191 is engaged by an actuating lever 197 which has a limited pivotal movement and serves to limit the downward movement of the slide. The lever 197 is mounted on a pivot pin 198 which passes through the lever intermediate its ends and is carried by a suitable bracket 199 fixed to the under side of the casing 153. The inner end of the lever 197 is engaged by an actuating pin 200 which is slideable vertically within the casing and is positioned in alignment with the pawl arm 179 through which the wire feeding roll is actuated. The pin 200 has a head 201 at its lower end which engages with the bottom of the casing 153 to limit the upward movement of the pin and the head 201 is engaged by a set screw 202 in the rear end of the lever 197. By adjusting the set screw 202 the throw of the cutter slide 191 may be adjusted. For actuating the vertical pin 200, the ratchet arm 179 has a radially disposed spring pressed plunger 203 which projects beyond the outer end of the arm and is pressed outwardly by means of a suitable coil spring 204, the outward movement of the plunger 203 being limited by a suitable set screw 205 in the arm 179 which engages a suitable groove in the plunger. During the upward movement of the rack bar 76, the arm 179 swings downwardly beneath the shaft 174 and forwardly toward the pin 200 until the spring pressed plunger 203 engages with the pin 200 and springs into a notch 206 in the upper portion of the pin 200. The angular movement of the arm

179 during the upward movement of the rack bar 76 is just sufficient to bring the plunger 203 into engagement with the notch 206 of the pin 200. As above explained, the 5 upward movement of the rack bar 76 actuates the wire feeding mechanism to feed forward a given length of wire. Immediately upon the beginning of the downward movement of the rack bar 76, the plunger 203 10 forces the pin 200 downwardly, rocking the lever 197 about its pivot 198 and forcing the cutter slide 191 upwardly so that its cutting edge moves across the wire feeding aperture 172, severing the wire. After a limited 15 downward movement, the plunger 203 moves out of engagement with the notch 206 in the pin 200 and the spring 195 returns the cutter slide 191, the lever 197 and the actuating pin 200 back to their normal position.

20 Referring to Figs. 3 and 20 to 23 inclusive, the wire tying mechanism is carried by a casing 207 attached to a fixed supporting bracket 208 mounted upon the framework of the machine. The function of the 25 tying mechanism is to grip the vertically disposed ends of the wire that have been wrapped about a pack of slips by the wrapping mechanism F and to tie the wire by twisting the ends together. The tying mechanism consists of a pair of wire gripping jaws 209 which are first actuated to grip the wire and then rotated to twist the same. The jaws 209 are suspended from horizontal pivot pins 210 mounted in a rotatable casing 211 supported beneath the casing 207. The upper ends of the jaws 209 have lugs 212 projecting outwardly from the pivots 210 which are adapted to be engaged by downwardly projecting lugs 213 carried 30 by a slide block 214 in the casing 211, the block 214 being attached to the lower end of a cylindrical slide 215 in a vertical bore formed in the casing. The casing 207 has a lower section 216 in which the 35 slide 215 is mounted and an upper section 218 to which the lower section 216 is attached by means of bolts 219. The upper section 218 has an enlarged bore 220 directly over the bore in the lower section 216 in which the slide 215 is mounted and the slide 215 is provided with a collar 221 rigidly secured at its upper end within the bore 220 and engageable with the lower section 216 of the casing to limit the downward movement of the slide 215. The slide 215 has an axial bore 222 from the upper end thereof, which receives a hollow cylindrical slide 223 which normally extends to the top of the bore 222 and has a plug 224 closing its upper end. The cylindrical slide 223 is supported in the bore 222 by means of a compression coil spring 225 which bears at its upper end against the under side of the slide 223 and at its lower end upon the bottom 40 of the bore 222. Within the bore 220 in

the upper section 218 of the casing is mounted a slide 226 which is provided with a transverse slot in its upper face to receive the actuating slide bar 71 and has pins 228 projecting into the slot from opposite sides 70 thereof and engaging in cam forming grooves in opposite faces of the slide bar 71. The cams formed in the sides of the slide bar 71 have inclined end portions 229 and 230 at the front and rear ends thereof, 75 the inclined faces 229 engaging the pins 228 to force the slide 226 downwardly and the inclined faces 230 engaging the pins 228 upon the return movement of the slide 71 to lift the slide 226. During the forward 80 stroke of the slide 71 the vertically moving slide 226 is forced to its lowermost position, pressing the hollow slide 223 downwardly and through the spring 225, depressing the slide 215 which carries the lugs 213 which 85 actuate the gripping jaws. Thus during the forward movement of the slide 71, the jaws 209 are moved to and held in wire gripping position, the spring 225 serving to transmit a yielding pressure to the jaws so that they 90 will not cut the wire.

For returning the jaws to open position after they have been released by the return movement of the slide 71, a hollow cylindrical slide 231 is mounted in a counterbore at 95 the bottom of the slide 215 and has a pin 231 slidable therein and projecting below the lower end thereof. The pin 232 is disposed centrally with respect to the jaw pivots 210 and has a head 233 at its lower end which 100 engages in notches 233 formed in the portions of the jaws 209 between the pivots 210. The pin 232 is held at all times in engagement with the notches 233 by means of a coil spring 234 within the hollow slide 231 105 which bears against the upper end of the pin. The upper end of the hollow slide 231 engages with a pin 235 which is slidable through the lower end of the upper hollow slide 223 and has a head 236 within the interior of the slide 223 which limits the 110 downward movement of the pin and which is normally pressed against the bottom of the bottom of the slide 223 by means of a coil spring 237 which is interposed between the plug 224 and the head 236 of the pin. When the slide 215 is moved downwardly 115 to close the jaws 209, the pin 232 is moved upwardly against the action of the spring 234 within the slide 231 and is additionally cushioned by means of the spring 237 within the upper hollow slide 223 so that should the pin 232 bind within the slide 231, the slide 231 can move bodily against the pressure of the spring 237.

For imparting rotary movement to the jaws 209 the upper end of the slide 215 has formed therein elongated gear teeth 238 which are in sliding mesh with a gear 239 fixed to a vertical shaft 240 at one side of 120

the slide. The shaft 240 has an enlarged upper end 241 which rotates within an enlarged bore in the upper section 218 of the casing and which has formed therein adjacent its upper end, gear teeth 242 which mesh with a rack 243 which is actuated by the slide 71. For actuating the rack bar 243 the slide 71 has spaced rearwardly projecting arms 244 projecting inwardly therefrom which are adapted to engage with an arm 245 attached to the rack bar 243 and projecting upwardly through an elongated slot 246 in the top of the casing. The arms 244 are spaced apart a sufficient distance to provide a certain amount of lost motion between the slide 71 and the rack bar 243 so that the rack bar 243 is not actuated in a forward direction until after the slide 71 has moved far enough to cause the jaws 209 to grip the wire, and the rack bar 243 is not shifted rearwardly until after the slide bar 71 has moved rearwardly far enough to release the jaws 209 so that the rotary movement of the jaws 209 does not commence until the jaws have firmly gripped the wire and the reverse rotation of the jaws does not occur until after the jaws have been actuated to release the wire. The arms 244 have set screws 247 which engage with the rack bar arms 245 and which may be adjusted to vary the extent of movement of the rack bar 243 to give more or fewer twists to the wire. Rigidly attached to the lower section 216 of the casing and projecting downwardly therefrom are wire guides 248 which have horizontal lower portions 249 bent inwardly beneath the wire gripping jaws 209. The portions 249 of the wire guides are disposed upon opposite sides of the axis of rotation of the jaws and are provided with inclined portions 250 which serve to guide the wire inwardly toward the axis of rotation of the jaws and with abutments 251 at their inner ends which are disposed parallel with the wire guides and which serve to hold the wire centrally upon the pack while the wire is being twisted by the tying mechanism. The abutments 251 prevent the wire from being shifted angularly across the top of the pack and causes the wire to be drawn down against the top of the pack in the plane of the portions of the wire extending around the slides and bottom of the pack.

In the operation of the machine the desired number of plates will be connected in the endless chain A and the lug 42 will be placed upon the last plate of the series, the lever 40 being so disposed that it will be engaged by the lug 42 as the last slip of each series is delivered to the magazine 2. At the instant each slip is severed by the knife 4, it will be engaged by the striker arms 13 and forced down in the magazine past the latches 9 into engagement with the slips accumulated upon the follower 5. This operation is continued until the last slip of a series is delivered to the magazine whereupon the lug 42 will engage the trip lever 40 to effect the release of the stripper 70. Since this machine is very rapid in its operation, the slips being delivered to the magazine 2 at the rate of 1000 or more per minute, it is necessary that the movement of the stripper be timed with extreme accuracy in order to enable the magazine to be completely emptied and the parts returned to receiving position in time to receive the succeeding slip when it has been severed by the knife 4. Means have therefore been provided to release the stripper arm 20 at the instant when the last slip of a series has been severed. To accomplish this result the trip lever 40 is connected to the trip member 37 which is moved 75 into the path of the striker plate 41 instead of being directly connected to the stripper releasing means, the striker plate 41 being positioned to always engage the trip arm 37 when the same is in tripping position at the instant when a strip has been severed. Upon release of the stripper arm 20, it is jerked down by the strong spiral spring 30^a and moved inwardly into 80 engagement with the pack by the cam 25 carrying the follower 5 down into the carriage E until the ends of the pack are engaged by the adjustable supporting ledges 83. At the end of its downward movement, the stripper slide 27 engages the lever 43 and releases the retaining hooks 88 on the carriage which spring into engagement with the pack so that the pack is securely held upon the upward movement of the stripper hook 20 which immediately follows. At the 85 same time the cam shaft 58 starts its rotation, the clutch 50 having been thrown in by the means hereinbefore described. At the instant the cams begin their revolution, the stripper is returned to uppermost position and reset by means of the links 77 and 77^a connected to the rear end of the cam actuated lever 74. As the carriage E is moved forwardly it carries the pack of slips off of the follower 5 so that the follower 5 can be snapped back by its spring to receiving position. At the beginning of the revolution of the cams the wire feeding mechanism is also started into operation to deliver a suitable length of wire to the 90 wrapping mechanism, the wire from the feeding mechanism moving into the wrapping mechanism from one side thereof and the transfer carriage carrying the pack toward the wrapping mechanism from the opposite side thereof. To prevent interference between the wire projecting through the wire guides of the wrapping mechanism and the transfer carriage, a suitable fixed support plate 253 extends from the wrapping 95

100

105

110

115

120

125

130

mechanism through the lower portion of the carriage E beneath the pack supported by the ledges 83. The end of the wire which is fed through the wrapping mechanism 5 rests upon the plate 253 which is spaced sufficiently beneath the ledges 83 in any position thereof so that there is no danger of the wire engaging the pack. The cam controlling the movement of the carriage E 10 is so designed that the carriage moves over the slide 103 of the wrapping mechanism and remains stationary until the slide 103 has completed its upward movement, so that the pack is firmly held by the hooks 88 of 15 the carriage while the wire is being wrapped about the pack. The cam controlling the operation of the wire feeding means is so designed that a piece of wire of the desired length has been fed to the wrapping 20 mechanism and severed before the slide 103 of the wrapping mechanism begins its upward movement. The cam controlling the operation of the wrapping mechanism starts the upward movement of the slide 103 at 25 the instant when the wire feeding operation is completed and the slide 103 in its movement wraps the wire about the bottom and sides of the bundle, the end portions of the wire being held within the retaining members 122 and 132 until the slide has completed 30 its upward movement and then released as hereinbefore explained. The operation of the wire tying mechanism begins when the slide 103 has reached its uppermost 35 position and the ends of the wire have sprung to vertical position, the tying operation being performed while the carriage E is returning to receiving position. While the stripper 20 is delivering the pack from the magazine 2 to the carriage E and while the follower 5 is moving down into the carriage and returning to its uppermost position in the magazine, the first slips of the succeeding series are delivered into the 40 magazine and are retained upon the spring actuated bars 10 which will retain a sufficient number of slips to give the follower ample time in which to return to receiving position before the slips are forced past the 45 bars 10.

Whenever the endless chain of plates A is built up with a greater or less number of plates, the proper tripping of the stripper is taken care of by the position of the actuating lug 42 but it is necessary if there is a considerable variation in the number of plates to make certain adjustments in the other mechanisms to accommodate larger or smaller packs. The carriage E is adjusted 55 to accommodate packs of different sizes by means of the vertical rack bars 84 which carry the pack supporting ledges 83 and which may be adjusted to dispose the ledges 83 at the proper height to accommodate the pack between said ledges 60.

and the hooks 88 by means of the hand wheel 98. In connection with the wrapping mechanism F, the only adjustment necessary is to substitute a longer or shorter wire guide extension 124, a suitable number of 70 such extensions being carried in stock and an extension of suitable length for a given run being attached to the arm 106. The wire feeding mechanism is adjusted to feed different lengths of wire and is moved bodily toward and from the wrapping mechanism F so that the pieces of wire delivered therefrom will be properly centered with respect to the wrapping mechanism by means of the adjustable crank 184 controlling both the 75 adjustment of the ratchet guard for varying the extent of movement of the wire feeding rolls and the shifting of the wire feeding mechanism along the guide bar 155.

Having described my invention, I claim— 80

1. The combination with a slip receiving magazine, of means for feeding a continuous strip of sheet material toward said magazine, a cutter at one side of the magazine for cutting said strip into slips of predetermined length, and an oscillating striker having a direct mechanical connection with the cutter and oscillated thereby to engage and force each slip into the magazine after 85 it is severed by the cutter. 90

2. The combination with a slip receiving magazine, of means for continuously feeding slips thereto, means for periodically and automatically removing a predetermined number of slips from the magazine, and 100 means controlling the operation of the slip removing means which is adjustable to vary the number of slips removed at each operation of the slip removing means. 95

3. The combination with a magazine, of 105 means for continuously feeding slips thereto, a yielding follower in the magazine, slip retaining means engaging the slips to hold them in engagement with the follower, means for feeding the slips into the space 110 between the retaining means and follower, and means for removing from the magazine the slips held against the follower during an interval between the feeding of successive slips to the magazine. 115

4. The combination with a magazine, of means for continuously feeding slips thereto at a uniform rate, and an oscillating striker having a positive driving connection with the slip feeding means and oscillated thereby to strike each slip at the instant when it is delivered to the magazine. 120

5. The combination with a magazine, of means for continuously feeding slips edge-wise into the magazine, and an oscillating striker moving in a plane at right angles to the movement of the slips in entering the magazine, said striker having a crank and link connection with a part driven from the feeding means and timed to strike each slip 125 130

at the instant when it is delivered to the magazine.

6. The combination with a vertically disposed magazine, of means for feeding slips horizontally into the magazine, a horizontally disposed rock shaft at one side of the magazine, said shaft having a crank and link connection with a part driven from the feeding means, and a striker arm carried by said shaft, said striker arm being movable from a position above the point of entry of the slips and the movement thereof being so timed with respect to the feeding means that it is moved downwardly into engagement with each slip at the instant when the slip has completely entered the magazine.

7. The combination with a magazine, of means for continuously delivering slips to the magazine, a reciprocating ejector for periodically removing a pack of slips from the magazine, a trip controlling the actuation of the ejector, and means driven from the feeding means for actuating the trip.

8. The combination with a magazine, of means for continuously delivering slips to the magazine, means for periodically emptying the magazine, a trip controlling the slip removing means, means driven from the feeding means for actuating the trip and means controlled by a moving part of the feeding means for causing said trip actuating means to engage the trip.

9. The combination with a printing machine having a series of plates and means for successively moving the plates into engagement with a continuously moving strip of sheet material to print upon successive lengths of the strip, of a cutter at the discharge end of the machine for severing the strip in the spaces between the printed matter to form slips, a magazine adjacent the cutter to receive the slips, means for feeding the slips into the magazine, means for discharging slips from the magazine, and means controlled by the movement of the plates for controlling the operation of the slip discharging means.

10. The combination with a printing machine having a series of printing elements and means for successively moving said elements to printing position for continuously printing successive series of slips, each series comprising a predetermined number of slips, of a magazine to receive the slips from the printing machine, and means controlled by the printing machine for discharging each series of slips separately from the magazine.

11. The combination with a printing machine having a series of printing elements and means for successively moving said elements to printing position for printing successive series of slips upon a continuously moving strip of sheet material, of means

for severing the slips, means for feeding the severed slips into a magazine, and means controlled by the printing machine for discharging each series of slips separately from the magazine.

12. The combination with a printing machine having a series of printing elements and means for successively moving said elements to printing position for continuously printing successive series of slips, of a magazine to receive the slips, means for feeding the slips to the magazine, and means for removing each series of slips from the magazine during the interval between the delivery of the last slip of a series to the magazine and the entry of the first slip of the next series thereto.

13. The combination with a printing machine having a series of printing elements and means for successively moving said elements to printing position for printing successive series of slips upon a continuously moving strip of sheet material, of means for severing slips and delivering them to a magazine, and means for removing each series of slips from the magazine during the interval between the delivery of the last slip of a series to the magazine and the entry of the first slip of the next series thereto.

14. The combination with a printing machine having continuously driven printing means having a series of printing elements and means for successively moving said elements to printing position for continuously printing successive series of slips and continuously driven means for feeding a strip of sheet material to the printing means, of means for severing the strip in the spaces between the printed matter thereon, a magazine to receive the slips so formed, and means controlled by the printing means for periodically discharging each series of slips in a pack from the magazine.

15. The combination with a printing machine having means for continuously printing slips, a magazine to receive the slips, means driven from the printing machine for feeding the slips from the printing machine into the magazine, means for discharging the slips at intervals from the magazine, a trip controlling the operation of the discharging means, and means controlled by the printing means for periodically causing said trip to be actuated by said feeding means.

16. The combination with a printing machine having means for continuously printing successive series of slips, a magazine to receive the slips, means for feeding the slips from the printing machine into the magazine, means for discharging each series of slips separately from the magazine, a trip controlling the actuation of the discharging means, and means controlled by the printing means for actuating said trip.

17. The combination with a printing machine having means for continuously printing successive series of slips, a magazine to receive the slips, means for feeding the slips from the printing machine into the magazine, means for discharging each series of slips separately from the magazine, a trip controlling the actuation of the discharging means, a trip actuator continuously driven from the printing means, and means controlled by the printing means for causing said actuator to engage the trip.

18. The combination with a magazine, of means for feeding slips thereto, means for discharging at intervals a pack of slips from the magazine, a trip controlling the actuation of the discharging means and means for periodically causing said feeding means to actuate said trip.

19. The combination with a magazine, of means for feeding a continuous strip of sheet material to said magazine, a rotating blade driven from the feeding means and located at the receiving end of the magazine for severing said strip into slips and an oscillating striker connected by a crank and link with said knife to feed the severed strips into the magazine, said striker being so connected to the knife that it engages with the slip at the instant the slip is severed from the strip.

20. The combination with a magazine, of means for feeding a continuous strip of sheet material to said magazine, means at an end of the magazine for severing slips of a constant length from said strip, an oscillating feeder operated by the severing means, said feeder engaging each slip as it is severed and feeding it into the magazine, a stripper for emptying the magazine, a trip controlling the action of the stripper, means carried by the oscillating feeder for actuating the trip, a part carried by the trip adapted to be shifted into the path of the actuating means, and means for periodically shifting said part.

21. The combination with a magazine, of means for continuously feeding slips edge-wise into the magazine, a reciprocating feeder engaging each slip to feed the same into the magazine, means for maintaining the slips in the magazine in a compact pack comprising a yielding follower and latches for retaining the pack against the follower, a stripper engageable with the top of the pack to force the same together with the follower beyond the lower end of the magazine, and means for removing the pack from the follower.

22. The combination with a printing machine having a series of printing elements and means for successively moving said elements to printing position for continuously printing successive series of slips, means controlled by the printing means for collect-

ing each series of slips in a separate pack, and means for wrapping separately the packs so formed.

23. The combination with a printing machine having a series of printing elements and means for successively moving said elements to printing position for continuously printing successive series of slips, a magazine for receiving the slips from the printing machine, means associated with the magazine and controlled by the printing means for extracting slips therefrom in packs each containing a complete series of slips, wrapping mechanism, and means for transferring the packs to the wrapping mechanism, the operation of the transfer means and wrapping mechanism being controlled by said extracting means.

24. The combination with a printing machine having a series of printing elements and means for successively moving said elements to printing position for continuously printing successive series of slips, and means controlled by the printing means for collecting each series of slips into a separate pack and for wrapping separately the pack so formed.

25. The combination with a printing machine having a series of printing elements and means for successively moving said elements to printing position for continuously printing successive series of slips, a slip stacking magazine for receiving the slips from the magazine, and means controlled by the printing means for extracting the pack of slips from the magazine when a complete series has been delivered thereto and for wrapping the same while the next series of slips is being delivered to the magazine.

26. The combination with a printing machine having a series of printing elements and means for successively moving said elements to printing position for continuously printing successive series of slips, a magazine for receiving the slips from the printing machine, a wrapping mechanism, a transfer carriage, means for transferring a pack containing a series of slips from the magazine to the carriage, and means controlled by the printing means for operating the pack transferring means, shifting the carriage to the wrapping mechanism, operating the wrapping mechanism and returning the carriage to the magazine.

27. The combination with a printing machine having a series of printing elements and means for successively moving said elements to printing position for continuously printing successive series of slips, of means controlled by the printing means for collecting each series of slips in a separate pack and means for wrapping each pack while the next series of slips is accumulating in a second pack.

28. The combination with a printing machine having a series of printing elements and means for successively moving said elements to printing position for continuously printing successive series of slips, a magazine for receiving the slips from the printing machine, a wrapping mechanism, conveying means for transferring slips from the magazine to the wrapping means, means controlled by the printing means for discharging each series of slips in a pack from the magazine to the conveying means, means having a predetermined movement for actuating the conveying and wrapping means, and means controlled by the discharging means for operating said actuating means.
29. The combination with a printing machine having a series of printing elements and means for successively moving said elements to printing position for continuously printing successive series of slips, a magazine for receiving the slips from the printing machine, a wrapping mechanism, means for feeding lengths of wire to the wrapping mechanism, means for tying the wire, a transfer carriage for delivering packs of slips from the magazine to the wrapping mechanism, means having a predetermined movement for operating the transfer carriage, the wire feeding mechanism and the wrapping and tying mechanisms through a complete cycle of operations to transfer a pack from the magazine to wrap and tie the same and to return the parts to their original position, and means controlled by the printing means for transferring each series of slips in a pack from the magazine to the carriage and for controlling the actuation of said operating means.
30. The combination with a printing machine having a series of printing elements and means for successively moving said elements to printing position for continuously printing successive series of slips, said means being adjustable to vary the number of slips in a series, and means automatically controlled from the printing means for collecting each series of slips in a separate pack and wrapping the individual packs.
31. The combination with a printing machine having a series of printing elements and means for successively moving said elements to printing position for continuously printing successive series of slips, said means being adjustable to vary the number of slips in a series, and means automatically controlled from the printing means for collecting each series of slips in a pack as the slips are discharged from the machine and for wrapping each pack so collected while a succeeding series of slips are being printed.
32. The combination with a printing machine having a series of printing elements and means for successively moving said elements to printing position for continuously printing successive series of slips, said means being adjustable to vary the number of slips in a series, and pack forming transferring and wrapping means to which the slips are delivered from the machine, said means being automatically controlled from the printing means and adapted to deliver the slips with each series wrapped in a separate bundle, said transferring and wrapping means being adjustable for handling packs of different sizes.
33. The combination with a printing machine having a series of printing elements and means for successively moving said elements to printing position for continuously printing successive series of slips, said means being adjustable to vary the number of slips in a series, slip bundling means automatically controlled from the printing means comprising means for collecting each series of slips in a pack, means having predetermined cycles of operation for wrapping the packs and transferring the packs from the pack collecting means to the wrapping means, said transfer means and said wrapping means being adjustable to accommodate packs of different sizes.
34. The combination with a printing machine having a series of printing elements and means for successively moving said elements to printing position for continuously printing successive series of slips, means for collecting in a pack slips discharged from the machine, means moving when actuated through a complete cycle of operations for taking a pack from the collecting means, wrapping the same and returning to starting position, and a trip automatically actuated from the printing means for controlling said last mentioned means.
35. In a machine of the character described, a magazine, means for feeding slips to the magazine, a wrapping mechanism, means for transferring a pack of slips from the magazine and delivering the same to the wrapping mechanism, and means controlled by the feeding means for periodically operating said pack transferring means.
36. In a machine of the character described, a magazine, means for continuously feeding slips to the magazine, and means automatically actuated by the feeding means upon the delivery of a predetermined number of slips to the magazine to discharge said slips from the magazine and wrap the same while other slips are being accumulated in the magazine.
37. In a machine of the character described, a magazine, means for continuously feeding slips to the magazine, a stripper for discharging an accumulated pack of strips from the magazine, separately actuated means for receiving the packs discharged from the magazine and wrapping the same, and a single trip operated by the feeding

- means for controlling the operation of the stripper and wrapping means.
38. In a machine of the character described, the combination with a magazine for receiving slips, said magazine having a follower and means for holding the slips in a stack against said follower, of a transfer carriage adapted to be positioned beneath the magazine, means for continuously feeding slips to the magazine, means controlled by the feeding means for lowering the follower with the pack of slips thereon into the transfer carriage, means on the carriage for gripping the pack, and means for shifting the carriage laterally to free the pack from the follower.
39. In a machine of the character described, the combination with a magazine having a follower and means for holding slips in a pack against the follower, of means for continuously feeding slips to the magazine, a transfer carriage adapted in one position to form a continuation of the magazine, means controlled by the feeding means for periodically shifting the follower with the slips accumulated thereon into the carriage, and means for disengaging the follower from the pack and for retaining the pack in the carriage.
40. In a machine of the character described, the combination with a vertically disposed magazine having a vertically movable follower and means for holding slips in a pack against the follower, of means for continuously feeding slips horizontally into the top of the magazine and for forcing the slips downwardly against the follower, a periodically actuated stripper engageable with the top of the pack to shift the pack and follower beneath the lower end of the magazine, and means controlled by the movement of the stripper for removing the pack from the follower.
41. In a machine of the character described, the combination with a vertically disposed magazine having a vertically movable follower and means for holding slips in a pack against the follower, of means for continuously feeding slips edgewise into the top of the magazine and for forcing the slips downwardly against the follower, a reciprocating transfer carriage beneath the magazine, a spring actuated stripper engageable with the top of the pack of slips within the magazine, trip controlled means for retaining the stripper in uppermost position and clear of the pack, means actuated by the feeding means for periodically tripping the stripper, means actuated upon downward movement of the stripper for shifting the carriage laterally to free the follower, means carried by the carriage and actuated upon the lateral movement thereof to engage the pack to retain the same in the carriage, and means operable upon return movement of the carriage to return the stripper to its original position.
42. In a machine of the character described, the combination with a magazine, of means for continuously feeding slips to the magazine and accumulating the same in a pack therein, a spring actuated stripper for periodically discharging the accumulated slips from the magazine, a trip device adapted to be actuated by the feeding means for releasing the stripper, conveying means for receiving the packs discharged from the magazine, and means operated by the conveying means for resetting the stripper.
43. In a machine of the character described, the combination with a magazine, of means for continuously feeding slips to the magazine and accumulating the same in a pack therein, a trip controlled device for periodically discharging an accumulated pack of slips from the magazine while the next succeeding slip is being fed into the magazine, a transfer device for receiving the slips from the magazine, and means for automatically controlling said devices from said feeding means.
44. In a machine of the character described, the combination with a vertical slip receiving magazine having a spring pressed follower and retaining latches above the follower, of means for continuously feeding slips horizontally into the top of the magazine and for forcing individual slips as they are fed to the magazine downwardly past the retaining latches into a pack on the follower stripper having a portion adapted to engage the top of a pack held between the latches and follower and to force the pack and follower below the bottom of the magazine, means for holding the stripper in pack engaging position during its downward movement and clear of the magazine during its upward movement, means for periodically actuating the stripper, and means for removing the pack from the follower.
45. In a machine of the character described, the combination with a magazine, of means for continuously feeding slips thereto, conveying means, means for periodically discharging a pack of accumulated slips from the magazine to the conveying means during an interval between the entry of successive slips thereto, and means for discharging the conveying means and returning the same to receiving position in the interval between successive actuations of the discharging means.
46. In a machine of the character described, the combination with a magazine having a follower and means for holding slips in the magazine against the follower, of means for continuously feeding slips to the magazine and accumulating them in a pack upon the follower, a wrapping mechanism, a carriage reciprocating between the

- magazine and wrapping mechanism, means for periodically discharging a pack of slips from the magazine to the carriage, and means for shifting said carriage to the wrapping mechanism, transferring the pack to the wrapping mechanism and returning the carriage to its receiving position in the interval between successive operations of the discharging means.
47. In a machine of the character described, the combination with a continuously operating slip discharging mechanism, of continuously operating means for accumulating discharged slips in a pack, wrapping means, means for transferring each pack when a predetermined number of slips have accumulated therein to the wrapping means, and means for operating said transferring and wrapping means through a complete cycle of operations and stopping the same while a second pack is accumulating in the magazine.
48. In a machine of the character described, a magazine for receiving slips, a laterally movable transfer carriage adapted to form in one position thereof an extension of the magazine, means for forcing a stack of slips from the magazine to the carriage and means carried by the carriage for engaging the top of the pack upon lateral movement of the carriage.
49. In a machine of the character described, a magazine, means for feeding slips to the magazine, a spring actuated follower in the magazine, means for advancing slips in the magazine toward the follower, means for retaining the slips in a pack against the follower, a transfer carriage adapted to be positioned in alignment with the discharge end of the magazine, a stripper periodically engaging the pack to force the same with the follower into the carriage, and means controlled by the movement of the stripper for disengaging the pack from the stripper and follower.
50. In a machine of the character described, a magazine, means for feeding slips to the magazine, a spring actuated follower in the magazine, means for continuously advancing slips in the magazine toward the follower and for retaining the slips in a pack against the follower, a transfer carriage having channel standards adapted to be aligned with the magazine and receive packs of slips therefrom, pack retaining hooks carried by the carriage and adapted to engage the top of a pack to retain the pack under compression in the carriage, means for normally holding the carriage in alignment with the magazine and said hooks clear of the pack receiving portion of the carriage, a stripper periodically engageable with a pack to force the same with the follower from the magazine into the carriage, and means controlled by the movement of the stripper for freeing the pack from the stripper and follower and engaging said hooks therewith.
51. In a machine of the character described, the combination with a magazine, a transfer carriage adapted to be positioned in alignment with the discharge end of the magazine and in such position forming a continuation of the magazine, means for continuously feeding slips to the magazine, means controlled by the feeding means for periodically transferring a pack containing a predetermined number of slips from the magazine to the carriage, said controlling means being adjustable to vary the number of slips in the packs delivered to the carriage, retaining hooks carried by the carriage, means for normally holding the carriage in receiving position and said hooks in retracted position, means controlled by the transferring means for shifting the carriage and for causing the hooks to engage the pack thereon, and means for adjusting the carriage to accommodate packs of different sizes.
52. In a machine of the character described, the combination with a magazine, of means for continuously feeding slips thereto and accumulating the slips so fed in a pack within the magazine, a wrapping mechanism, a transfer carriage, means for periodically transferring a pack of slips from the magazine to the carriage and for shifting the carriage to the wrapping mechanism, and means on the carriage for holding the pack during the wrapping operation.
53. In a machine of the character described, the combination with a magazine, of means for continuously feeding slips thereto and accumulating the slips so fed in a pack within the magazine, a wrapping mechanism, a transfer carriage, means for periodically transferring a pack from the magazine to the carriage, means for moving said carriage from the magazine to the wrapping means, holding said carriage stationary for a predetermined period at the wrapping mechanism and for returning said carriage to the magazine, and a trip actuated by the transferring means for controlling the operation of the carriage.
54. In a machine of the character described, the combination with a magazine, of means for continuously feeding slips thereto and accumulating the slips so fed in a pack within the magazine, a wrapping mechanism having a slide engageable with opposite sides of a pack, a transfer carriage having channel standards adapted to receive the ends of a pack and retaining hooks adapted to engage the top of a pack, means for normally holding said carriage beneath the magazine in a position to receive a pack of slips from the magazine and said hooks in disengaging position, means controlled by the feeding means for periodically discharging.

ing a pack from the magazine to the carriage, and releasing the hooks, means controlled by the discharging means for shifting the carriage from the magazine to the wrapping mechanism, operating the wrapping mechanism and returning the carriage to the magazine, and means controlled by the return movement of the carriage for shifting the retaining hooks out of engaging position.

55. In a machine of the character described, the combination with means for continuously feeding slips of a magazine to receive the slips, means associated with the magazine for continuously accumulating the slips in a pack, a stripper controlled by the feeding means for periodically discharging the accumulated pack from the magazine, a wrapping mechanism, a wire feeding mechanism associated with the wrapping mechanism, a wire tying mechanism, a transfer carriage normally positioned to receive a pack of slips from the magazine, and means controlled by the stripper for operating the carriage, wire feeding, wrapping and tying mechanisms through a complete cycle for wrapping the pack discharged and returning the carriage to receiving position and said stripper to its original position.

56. In a machine of the character described, a magazine, means for feeding slips thereto, a spring actuated discharger for said magazine, retaining means adapted to be actuated by the feeding means for releasing the discharger, a shaft having a series of cams, a clutch controlling the operation of said shaft, a trip adapted to be actuated by the discharger for engaging said clutch, transferring and wrapping mechanisms, and means operated by said cams for actuating said mechanisms and for returning said discharger to normal position.

57. In a mechanism of the character described, the combination with a magazine and means for continuously feeding slips thereto, of means for periodically removing the accumulated slips from the magazine and wrapping the same, comprising a discharging device, a transfer device, a wire feeding mechanism, a wrapping mechanism and a tying mechanism, and means controlled by the feeding means for operating said devices and mechanisms sequentially and each through a complete cycle of operations and stopping the same each in the position which it occupied at the beginning of the operation.

58. In a machine of the character described, the combination with a magazine and means for continuously feeding slips thereto, of a carriage adapted to receive slips from the magazine, a wrapping mechanism, means for moving the carriage from the magazine to the wrapping means and returning the same to the magazine, means

on the carriage for holding the pack during the wrapping operation, and means on the wrapping mechanism, engageable with the slips to discharge the same from the carriage on the return movement of the carriage.

59. In a machine of the character described, the combination with a machine for continuously feeding slips, of means for accumulating the slips in a pack, a transfer carriage, means for periodically transferring a pack of slips to the carriage, a wrapping mechanism, a wire feeding mechanism, a wire tying mechanism, means for shifting the carriage to and from the wrapping mechanism with a dwell at the wrapping mechanism, means for actuating the wire feeding mechanism during the movement of the carriage to the wrapping mechanism, means for actuating the wrapping mechanism during the dwell of the carriage, and means for actuating the tying mechanism during the return of the carriage.

60. In a machine of the character described, the combination with a machine for continuously feeding slips, of a magazine and means for accumulating the slips in a pack within the magazine, a transfer carriage, a spring actuated discharging device for periodically discharging a pack of slips from the magazine to the transfer carriage, a wrapping mechanism, a wire feeding mechanism, a tying mechanism, means for shifting the carriage to and from the wrapping mechanism with a dwell at the wrapping mechanism, operating the wire feeding mechanism during the movement of the carriage to the wrapping mechanism, operating the wrapping mechanism during the dwell of the carriage, operating the tying mechanism during the return of the carriage, a trip adapted to be periodically actuated by the feeding means, for releasing the discharging device, a trip adapted to be actuated by the discharging device for controlling the operation of the carriage and wrapping, means for automatically resetting said trip, wire feeding and tying mechanisms, and means operated by the carriage in its return movement for resetting said last mentioned trip.

61. The combination with a machine for feeding slips having a magazine to receive the slips therefrom of means for extracting the slips from the magazine and bundling the same comprising a transfer mechanism, a wrapping mechanism, a wire feeding mechanism and a tying mechanism, and means for periodically actuating said mechanisms through a complete cycle to wrap a pack of slips and to return the mechanisms to starting position for operating upon a succeeding pack.

62. The combination with a vertically disposed magazine, of means for continuously feeding slips thereto and stacking the slips

therein, a carriage mounted for horizontal movement beneath the magazine, said carriage having channel standards adapted to be aligned with the magazine to receive 5 packs of slips therefrom, a wrapping mechanism, having a vertically movable slide adapted to engage opposite sides of a pack, means on the carriage for engaging the top of a pack of slips therein, means for shifting 10 the carriage from the magazine to a position over the slide and back to the magazine with a dwell over the slide of the wrapping mechanism, and means for actuating the slide of the wrapping mechanism while the carriage 15 is above the same to engage the pack and for retaining the slide in elevated position during the start of the return movement of the carriage, the forward flanges of the standards of the carriage being yieldable to 20 release the pack engaged by the slide.

63. The combination with a magazine, of means for continuously feeding slips thereto and stacking the slips therein, a carriage mounted for horizontal movement beneath the magazine, means for discharging 25 slips from the magazine to the carriage, a wrapping mechanism, a cam connected to the carriage and adapted in one revolution to shift the carriage from the magazine to 30 the wrapping mechanism and from the wrapping mechanism to the magazine, a trip controlling the operation of the cam adapted to be actuated by the magazine discharging means, and means operated by the carriage at the end of its return movement for 35 resetting the trip and stopping the rotation of the cam.

64. In a machine of the character described, the combination with a magazine 40 and means for continuously feeding and stacking slips therein, means for periodically discharging a pack of slips from the magazine, pack transfer, wire feeding, wire wrapping and wire tying mechanisms adapted to act sequentially upon a pack of slips 45 discharged from the magazine, and means including a shaft having cams thereon one connected to each of said mechanisms, and trip controlled means for turning said shaft 50 through one revolution, said cams operating during the revolution thereof to shift the pack from the magazine to the wrapping mechanism, to actuate the wire feeding mechanism to feed a length of wire to the 55 wrapping mechanism, to operate the tying mechanism and return the transfer mechanism to receiving position.

65. In a machine of the character described, a wrapping mechanism, means for periodically delivering packs of slips thereto, means 60 for feeding lengths of wire thereto, said wire feeding means comprising wire feeding rolls and a wire cutter, a reciprocating rack bar adapted upon movement in one direction to 65 actuate the rolls and upon return movement

to actuate the cutter, and means controlled by the pack delivery means for causing the rack bar to be reciprocated.

66. The combination with a wrapping mechanism, of means for periodically delivering a pack of slips to the wrapping mechanism, means for feeding wire to the wrapping mechanism and for severing a suitable length of wire, and means for adjusting 70 said wire feeding means to increase or decrease the length of the pieces of wire fed, and means for simultaneously shifting the wire feeder from or toward the wrapping mechanism. 75

67. The combination with a wire wrapping mechanism, of means for periodically delivering bundles thereto to be wrapped, a wire feeding mechanism having wire feeding and severing means, means controlled by the transferring means for actuating the 80 wire feeding means, means for shifting the wire feeding mechanism toward or from the wrapping means and for simultaneously decreasing or increasing the extent of movement of the wire feeding means. 85

68. In a machine of the character described, a wrapping mechanism, comprising a slide with a slot therein to receive a bundle, wire guides in the slide on opposite sides of the slot, means for feeding suitable lengths 90 of wire into said guides, and across the slot prior to the operation of the slide, means for periodically delivering a bundle and holding the same in alignment with the slot, means for actuating the slide to enter the bundle 95 into the slot, means associated with the wire guides for retaining the ends of the wire therein during the movement of the slide, means acting on the wire retaining means to release the ends of the wire upon the completion of the upward movement of the slide, and wire tying means adapted to engage the 100 ends of the wire upon the release thereof. 105

69. In a machine of the character described, a wrapping mechanism comprising a slide with a slot extending from the end thereof and a follower in the slot, means for periodically placing a bundle on the follower and holding the same thereon, means for actuating the slide to enter the bundle in the 110 slot, wire guiding means in the slide and block, and means for feeding a length of wire into the guiding means prior to the actuation of the slide, and wire tying means engageable with the free ends of the wire 115 at the end of the stroke of the slide. 120

70. The combination with a wrapping mechanism comprising a slide having a slot extending from an end thereof and a follower in the slot, of means for periodically shifting a bundle into engagement with the follower and holding the same in alignment with the slot, means operating simultaneously with the bundle shifting means for feeding a suitable length of wire across the 125 130

slot, means for actuating the slide to enter the bundle in the slot and wrap the wire about the bundle, wire tying means engageable with the wire at the completion of the 5 wrapping stroke and means for operating the tying means during the return movement of the slide.

71. The combination with a wrapping mechanism, of means for feeding a suitable 10 length of wire thereto, means for feeding a bundle thereto, means for actuating the wrapping mechanism to wrap the wire about the bundle, a wire twisting mechanism, and means for operating the twisting mechanism 15 after the wire has been wrapped, and means for holding the wire adjacent the bundle against angular movement during the twisting operation.

72. The combination with a wrapping 20 mechanism comprising a slide having a slot extending from an end thereof and a follower in the slot, aligned tubular wire guides in the slide on opposite sides of the slot, and a tubular wire guide in the follower which 25 is normally aligned with the wire guides at the sides of the slot, said wire guides having longitudinal slots, and means for normally closing said slots, of means for feeding suitable lengths of wire to the guides, means for 30 delivering a bundle to the follower and holding the same against movement with the slide to enter the same in the slot, means controlled by the movement of the slide for uncovering said slots to release the ends of 35 the wire, and means for tying the wire.

73. The combination with a wire wrapping means, of means for feeding suitable 40 lengths of wire thereto, means for periodically delivering bundles thereto, means for tying the wire, a shaft having a cam connected to each of said means, and trip controlled means for turning the shaft through a complete operation and stopping the same, said cams being so connected to said means 45 that the means are each actuated in the proper sequence through a complete cycle and are stopped in the positions from which they started.

74. The combination with a wrapping 50 mechanism, a wire feeding mechanism comprising wire feeding rolls, a rack bar, means connecting said rack bar and rolls for actuating the rolls upon movement of the rack bar in one direction, a wire cutter, and means 55 for actuating said cutter upon the movement of the rack bar in the opposite direction.

75. The combination with a wrapping 60 mechanism, of a wire feeding mechanism comprising wire feeding rolls, a rack bar, means connecting said rack bar and rolls for actuating the rolls upon movement of the rack bar in one direction, said means being adjustable to vary the feeding movement of 65 the rolls, a wire cutter, and means for actu-

ating said cutter upon the movement of the rack bar in the opposite direction.

76. The combination with a wrapping mechanism of a wire feeding mechanism comprising wire feeding rolls, a rack bar, means connecting said rack bar and rolls for actuating the rolls upon movement of the rack bar in one direction, a wire cutter, means for actuating said cutter upon the movement of the rack bar in the opposite direction, and means for adjusting the roll actuating means to vary the length of wire fed by the rolls and for simultaneously adjusting the wire feeder bodily toward or from the wrapping mechanism. 75

77. The combination with a wrapping mechanism, of a wire feeding mechanism comprising wire feeding rolls, a rack bar, means including a pawl and ratchet for actuating the rolls upon movement of the rack bar in one direction, a wire cutter, means for actuating the cutter upon reverse movement of the rack bar, an arcuate guard for the ratchet, means for angularly adjusting the guard to vary the rotation of the rolls, and means operated by the last mentioned means for moving the wire feeding mechanism bodily toward or from the wrapping mechanism. 95

78. The combination with a wrapping mechanism, of a wire feeding mechanism 95 comprising wire feeding rolls, a rack bar, means for actuating the rolls to feed wire to the wrapping mechanism upon movement of the rack bar in one direction, a wire cutter, and means operated by the rack bar at the beginning of its return movement for actuating the cutter. 100

79. The combination with a wrapping mechanism, of a wire feeder for delivering lengths of wire thereto comprising a slidably mounted casing, a rack bar upon which the casing slides toward or from the wrapping mechanism, wire feeding rolls mounted upon the outside of the casing, a shaft extending through the casing, a sleeve on the shaft, a gear on the sleeve, a rack bar meshing with the gear, a gear loose on the shaft, a ratchet fixed to the gear, an arm fixed to the sleeve having a pawl engaging the ratchet, means for driving one of the rolls 115 from the last mentioned gear, a wire cutter in advance of the rolls, means for actuating the cutter from the rack bar at the beginning of the return movement of the rack bar, an arcuate ratchet guard fixed to said shaft, a handle fixed to the shaft outside the casing, means for securing the handle in various angular positions, and a gear fixed to the shaft and meshing with the rack bar upon which the casing slides. 120

80. The combination with a wrapping mechanism, of means for feeding lengths of wire thereto and a wire tying mechanism having a pair of jaws adapted to grip the ends of the wire after the same has been 130

wrapped about three sides of the bundle, means for actuating the jaws comprising a slide and means for closing the jaws from the slide and means for rotating the jaws 5 from the slide.

81. The combination with means for wrapping a length of wire about three sides of a bundle, of tying means comprising a pair of jaws between which the free ends of the wire 10 extend, means for actuating said jaws comprising a reciprocating slide, means for yieldingly actuating said jaws to close the same and for rotating the jaws upon movement of the slide in one direction, and means 15 for releasing the jaws.

82. The combination with means for wrapping a length of wire about three sides of a bundle, of a wire tying means comprising jaws between which the free ends of 20 the wire extend, means for closing the jaws and rotating the same, and fixed wire guiding means engageable with the wire ends between the jaws and bundle to guide the same to the center of the bundle and to hold the 25 wire centrally of the bundle during the twisting operation.

83. In a machine of the character described, a carriage having a forwardly offset bundle receiving portion provided with 30 bundle supporting ledges, a wrapping mechanism having a slide with arms engageable with opposite sides of the bundle on the carriage and a follower engageable with the bottom of a bundle on the carriage, wire guides 35 on the ends of the arms and in the follower, and means for moving the carriage over the slide and holding the same in position over the slide, means for actuating the slide, and means for delivering wire to the wrapping 40 mechanism.

84. In a machine of the character described, a wrapping mechanism comprising a slide having spaced arms, a follower between the arms, aligned transverse bores in 45 the top portions of the arms with slots extending across the tops of the arms, a transverse bore in the top portion of the follower, means for normally holding the follower in a position in which the bore therein aligns 50 with the bores in the arms, cylindrical wire guides in each of said bores with a longitudinal groove adapted in one position to align with the slots, means for normally holding said wire guide in a position in

which the grooves are out of alignment with 55 the slots, and means for actuating the slide, means for holding a bundle in position over the follower of the slide, means for feeding a length of wire into the guides, means for moving the follower guide to bring its 60 groove into alignment with the slot to release the wire upon engagement of the follower with the bundle, and means for moving the wire guides of the arms to releasing position as the slide approaches the end of 65 its stroke.

85. The combination with a printing machine having a series of plates in an endless chain adapted to print successive series of slips, each series corresponding in number 70 to the number of plates, said endless chain having any desired number of plates, of pack forming, transferring, wrapping, wire feeding and tying means controlled by said endless chain for separating each series of slips 75 discharged from the machine into a separate pack and wrapping and tying the same, said transferring, wrapping, wire feeding and tying means each being adjustable to handle 80 packs of different sizes.

86. The combination with a printing machine having an endless chain of plates and means for bringing said plates successively into engagement with a continuous strip of sheet material fed through the machine, of 85 a cutter driven from the printing machine for severing the strip into slips, a magazine to receive the slips and means driven from the printing machine for feeding the slips into the magazine, means for discharging 90 a pack of slips accumulated in the magazine, means for discharging a pack of slips accumulated in the magazine, a trip controlled by said endless chain for controlling the 95 operation of said discharging means, means for receiving a pack discharged from the magazine, wrapping a wire about the same and tying the wire, actuating means for said pack receiving wrapping and tying means adapted to operate the same through a complete cycle of operations and stop the same 100 with all parts in the position originally occupied, and a trip controlled from the printing means for controlling the operation 105 of the actuating means.

In testimony whereof, I hereunto affix my signature.

GEORGE L. FULK.
